FLEXIBLE OIL CAN

Einar Oakland, Long Beach, Calif.

Application December 9, 1950, Serial No. 200,003

2 Claims. (Cl. 222—215)

The present invention relates to the field of oiling devices, and more particularly to an oil can that is fabricated from a resilient deformable plastic material.

Although oil cans as such are relatively old, the design and construction of such devices has varied little over the years. As is well known, the present day oil can includes an elongated spout that is in communication with an oil holding container.

Such an oil can is normally constructed from brass, copper or a suitable copper containing alloy. An oil can fabricated from a copper containing metal has a tendency to accumulate a film of oil on the outer surface thereof that collects dust and dirt, and as a copper alloy is opaque it is impossible to determine the amount of fluid in a can without removing the spout therefrom.

A metallic oil can has the further disadvantage that being relatively small, it is destroyed or damaged by falling heavy objects in a machine shop or when run over by a vehicle in a service station or garage.

The primary purpose in devising the present invention is to provide an oil can that eliminates the disadvantages above mentioned.

A major object of the present invention is to supply an oil can which is deformable when subjected to an exterior force and which returns to its original shape when pressure is removed, is transparent or translucent to permit the quantity of fluid in the can to be easily determined at a glance, and is safe to use in that the flexible spout simply bends when it is accidentally contacted by an individual.

Another object of the invention is to furnish an oil can in which the tightness of the seal between the spout and fluid-holding container is increased as the spout is subjected to a pulling action or when the base of the spout is grasped between the fingers of the user and subjected to pressure.

A still further object of the invention is to provide an oil can that may be collapsed into a compact unit when shipped in quantity from the manufacturer to the distributor or retailer.

These and other objects and advantages of the invention will become apparent from the following description of the preferred form thereof, and from the drawing illustrating that form in which:

Figure 1 is a combined side elevational and vertical cross sectional view of the plastic oil can;

Figure 2 is a plan view of the device taken on line 2—2 of Figure 1;

Figure 3 is a horizontal cross sectional view of the spout taken on the line 3—3 of Figure 1;

Figure 4 is a combined side elevational and vertical cross sectional view of the oil can in a deformed position;

Figure 5 is a combined side elevational and vertical cross sectional view of the fluid containing portion of the invention showing the manner in which the container is deformed from its normal position to one that occupies considerably less space; and

2

Figure 6 is a combined side elevational and vertical cross sectional view of the fluid containing portion of the invention, and the mouth thereof sealed by a closure.

Referring now to Figures 1 and 2 for the general arrangement of the invention, it will be seen that it includes a tapering elongated spout S that is affixed to a fluid-holding container C. Both the spout and the container are preferably formed of one of the synthetic plastics, rubber, or a rubber-like material that is either transparent or translucent to permit the quantity of fluid F in the container to be ascertained without removal of the spout. Where a number of oil cans are in use in the same plant, garage, shop, or the like, with each can holding a different fluid, the container or spout, or both of the invention may be distinctly colored to indicate the type of fluid held therein.

The spout S is formed as an integral unit with an elongated member 10 through which a longitudinally extending bore 11 is formed and that is provided on one end with an annular cover 13 from which flange 14 depends. The cross sectional area of the bore 11 is of oval shape and gradually decreases as the bore approaches the upper free end of the spout S. It will be noted that the thickness of the side walls 12 of the spout likewise decrease in thickness as they approach the free end of the spout. When formed in such a manner the spout S may be bent into a curved position as shown in Figure 4, where it will remain for a sufficiently long period of time before returning to its initial position to permit the oiling of machine parts that are situated in cramped quarters. As seen in Figure 1, the cover 13 tapers upwardly slightly and the circumferentially extending flange 14 tapers inwardly in order to grip the mouth portion of the container C as will hereinafter be described.

Container C is preferably formed from a flat annular plate 16 from which side walls 17 extend upwardly. The vertical cross-sectional shape of the side walls 17, as may be seen in Figure 1, is substantially semi-spherical. Side walls 17 terminate at their upper ends in an annular flange 18 that tapers outwardly to substantially the same degree as flange 14 tapers inwardly. An opening 19 by which the container C is either filled or emptied, is defined by the inner face of the flange 18.

Plate 16 is relatively rigid compared to the material from which the balance of the invention is formed. Although sheet plastic may be used in the fabrication of plate 16, it has been found from experience that sheet brass, or the like, is more suitable for this purpose. A grooved portion 20 circumferentially extends around the plate 16 in which the lower end of side walls 17 are positioned.

A seal between the plate 16 and the lower edge of the side walls 17 is secured by any conventional bonding process such as heat, cement, or other means normally employed in effecting a seal between brass and a plastic material. Plate 16 may be made more resilient by forming an annular indented portion 21 therein as shown in Figure 1.

The use and operation of the invention is extremely simple. Fluid F is placed in the container C through the opening 19, and the flange 14 is then stretched to slip over the flange 18. Flange 18 is formed with a sufficiently heavy wall section as to be relatively rigid but somewhat deformable. The spout S is easily disengaged from the container C by slipping flanges 14 and 18 out of contact with one another. Should the spout S have an outward force exerted thereon to separate it from the container C, the diameters of cover 13 and flange 14 decrease, and flange 14 grips the exterior of flange 18 to prevent such separation. Thus, the possibility of fluid spilling from container C due to sudden lifting of the assembly by the spout S is eliminated.

When an oil can is used it is normally grasped between the thumb and second and third fingers of the hand. In the present invention the plate 16 is engaged by the thumb, and cover 13 engaged by the second and third fingers. As pressure is applied to plate 16 and cover 13, the space in container C decreases, causing the ejection of fluid F contained therein through spout S. Increased pressure on the fluid F will not cause it to leak from the container C, as pressure on cover 13 deforms the somewhat rigid flange 18 outwardly to increase its diameter and stretch flange 14 to form a fluid-tight seal therewith.

Substantially the maximum deformation of container C is shown in Figures 4 and 5. It will be noted in Figure 5 that as container C is deformed, the upper edge of flange 18 is lowered a distance L. This deformed shape of the container C is particularly useful as the spout S may be bent downwardly and caused to assume the curved position shown in phantom line in Figure 4. When so positioned the spout occupies an annular space 22 formed between flange 14 and side walls 17. It will be apparent that when in this form the invention occupies a minimum of space, as the top of flange 18 has been lowered a distance L, and the spout S is positioned in groove 22 to substantially occupy same. Thus, the invention may be stored in a minimum of space when not in use, and likewise transported with ease, and without danger of denting or damaging the cans while in transit.

When a flexible, tough plastic such as polyethylene manufactured by Du Pont de Nemours of Wilmington, Delaware, is used in the fabrication of the invention, the spout S and container C have sufficient resiliency to return to their normal shape after release from the distorted position shown in Figures 4 and 5. It will, of course, be apparent that fluid F is removed from the container C before deformation into the shape shown in Figures 4 and 5.

On occasion it may be desired to provide a closure for the container C. Such a closure 30 is shown in Figure 6 that includes a flat annular cover 13' from which a flange 14' depends downwardly and inwardly. The closure 30 is fabricated from a resilient plastic material with the result that the flange 18' is gripped in a fluid-tight seal by flange 14'. Downward pressure applied to the closure 30 simply increases the tightness of the seal between the flange 14' and flange 18 as previously described in connection with spout S.

Although the invention herein shown and described is fully capable of achieving the objects and providing the advantages hereinbefore mentioned, it is to be understood that it is merely illustrative of the presently preferred embodiment of the invention, and that it is not limited to the details of construction herein shown and described other than as defined in the appended claims.

The invention claimed is:

1. An oil can adapted to be disposed in a space-saving position when not in use which includes: a fluid-holding container having an annular bottom from which a continuous semi-spherical sidewall extends upwardly to terminate in an integrally formed tubular flange of substantial rigidity, said tubular flange having a smooth upwardly and outwardly extending exterior surface and an angularly disposed upper surface which define a sharp circumferentially extending edge at their junction, said sidewall being fabricated from a non-metallic flexible material of such thickness as to provide sufficient rigidity to

enable said sidewall to normally retain said semi-spherical shape, with said tubular flange being fabricated from a substantially rigid material; a tubular discharge spout formed from a non-metallic flexible material, with the wall thickness of said spout being sufficient to enable said spout to be self-supporting when said can is in an upright position, but said spout capable of being bent to fit within an annular recess formed in said sidewall when said neck is moved downwardly to bring the lower portion thereof into a position adjacent said bottom; a resilient downwardly and outwardly inclined annular cover integrally formed with the lower end portion of said spout; and a resilient flange of uniform thickness extending downwardly and inwardly from the circumferential edge portion of said annular cover to grip said tubular flange with sufficient force that said spout is not displaced from said container when said spout is disposed in said recess, the internal diameter of said resilient flange tending to contract upon application of outward force to said spout, with said tendency to contact causing said resilient flange to be anchored to said tubular flange.

2. An oil can adapted to be disposed in a space-saving position when not in use which includes: a fluid-holding container having an annular bottom from which a continuous semi-spherical sidewall extends upwardly to terminate in an integrally formed tubular flange of substantial rigidity, said tubular flange having a smooth upwardly and outwardly extending portion that terminates in a sharp circumferentially extending upper edge, said sidewall being fabricated from a non-metallic flexible material of such thickness as to provide sufficient rigidity to enable said sidewall to normally retain said semi-spherical shape, with said tubular flange being fabricated from a substantially rigid material; a tubular discharge spout formed from a non-metallic flexible material, with the wall thickness of said spout being sufficient to enable said spout to be self-supporting when said can is in an upright position, but said spout capable of being bent to fit within an annular recess formed in said sidewall when said tubular flange is moved downwardly to bring the lower portion thereof into a position adjacent said bottom; an annular cover integrally formed with the lower end portion of said spout; and a resilient flange of uniform thickness extending downwardly and inwardly from the circumferential edge portion of said cover to grip said tubular flange with sufficient force that said spout is not displaced from said container when said spout is disposed in said recess, the internal diameter of said resilient flange tending to contract upon application of outward force to said spout, with said tendency to contract causing said resilient flange to be anchored to said tubular flange.
